UNITED STATES PATENT OFFICE.

CHARLES ALBERT WETTENGEL, OF ST. LOUIS, MISSOURI.

MACHINE FOR CLEANING SHEET METAL.

SPECIFICATION forming part of Letters Patent No. 550,430, dated November 26, 1895.

Application filed August 19, 1892. Serial No. 443,537. (No model.)

To all whom it may concern:

Be it known that I, CHARLES ALBERT WETTENGEL, a citizen of the United States, residing at St. Louis, in the State of Missouri, have 5 invented certain new and useful Improvements in Machines for Cleaning Sheet Metal; and I do hereby declare the following to be a full, clear, and exact description of the invention, such as will enable others skilled in the 10 art to which it appertains to make and use the same.

My invention is a new and useful machine for cleaning and polishing sheet metal; and it consists in the novel features of construction and combination of parts hereinafter 15 fully described.

In the accompanying drawings I have shown one form in which I have contemplated embodying my invention and several slight modifications thereof, and said invention is fully disclosed in the following description and claims.

Referring to the said drawings, Figure 1 is a top plan view of a machine for cleaning and 25 polishing sheet metal embodying my invention. Fig. 2 is a rear elevation of the same. Fig. 3 is a central longitudinal vertical section of the machine. Fig. 4 is a detail view illustrating the arrangement of the cleaning 30 and polishing belts and their driving-chain. Fig. 5 is a top plan view of a slightly-modified form of machine. Fig. 6 is a view showing a slightly-modified arrangement of the cleaning and polishing belts and means for feeding absorbent material thereto. Fig. 7 is a detail view showing a different form of cleaning and 35 polishing belt. Fig. 8 is a view of a machine fitted with a different form of cleaning-belt and adapted for scouring and cleaning sheet metal. Fig. 9 is a top plan view of a portion 40 of a machine embodying my invention, showing driving devices for giving a reciprocating movement to the cleaning-belts. Fig. 10 is a side elevation of the same.

The object of my invention is to provide a 45 machine which will readily and effectively clean and polish sheet metal, and it is designed especially for cleaning and polishing sheet-tin after it leaves the bath of oil or tallow 50 to which it is subjected after passing through the tin-bath; but by making very slight changes it may be readily adapted for

cleaning the sheet-iron before it is tinned, as will be hereinafter described.

In the form of machine shown in Figs. 1 to 4, 55 inclusive, A represents the supporting framework, upon which are mounted two pairs of feeding-rollers, the feeding-in rollers B B and feeding-out rollers C C. On the outer side of the feeding-in rollers B B is located a box or receptacle D for the reception of absorbent material, and I provide means for reciprocating the said box to bring fresh portions of the material into contact with the sheet metal as it passes through, as indicated in dotted lines in 60 Fig. 1 and in full lines in Fig. 5. The side walls of the receptacle or box D are provided with horizontal slits or apertures d for the passage of the sheet of metal, and the said walls will preferably be cut away on the side 65 of the slit at which the sheet enters, in order to provide inclined surfaces d' d', which will serve to guide the front edge of the sheet to the slit d. The side walls of box D are provided with guides d² in the path of the metal 70 sheet for guiding the same in its passage through the box.

Between the feeding-in and feeding-out rollers are shown two pairs of horizontally-disposed cleaning and polishing belts E E and E' E', which are supported by rollers e e and e' e', suitably mounted in the machine. The belts will be so arranged that the horizontal portions of one of each pair will run adjacent to the horizontal portion of the other 85 and preferably in the opposite direction, and while any form of gearing may be employed for imparting motion to said rollers I prefer to gear each pair as shown in Fig. 4. In this figure one pair of belts is shown engaging 90 their supporting-rollers, and each roller has secured to its shaft or formed integrally therewith a sprocket-wheel e². A single driving-chain e³ engages the outside of the sprockets of the four rollers which support a pair 95 of belts, and by this arrangement the adjacent horizontal portions of the belts will travel in opposite directions, as indicated by the arrows, Fig. 4, and the full width between the centers of the rollers from one side of the machine to the other may be used for cleaning and polishing the metal.

When the machine is to be used for cleaning the grease from tin-plate and finishing

the same, I preferably employ belts E and E', made of sheepskin with the wool on the outside or of leather covered with sheepskin; but I may employ any other material which will 5 answer the purpose. The plates will be passed through the box D, which is filled with bran or other suitable material, and will become coated with the bran, which has a tendency to absorb the grease on the surface of 10 the tin. As soon as the plate emerges from the box D, it will pass between the feeding-in rollers which feed it forward. The rollers will hold it against lateral movement, and the reciprocation of the bran-box D will bring 15 fresh portions of the bran into contact with the plate as it passes through the box. Passing through the rollers B B the plate will be engaged on both sides by the cleaning and polishing belts, which will brush off the bran 20 or other material, taking most of the oil or grease with it, cleaning the tin. The plate then passes between the belts E' E', which further clean and polish the sheet, and it then passes between the feeding-out rollers 25 and out of the machine.

It will be seen that the belts operate transversely of the direction of travel of the plates through the machine, so that the bran or other material, together with the grease and 30 all dirt or other foreign matter, will be brushed laterally entirely off of the plate.

The belts operate in different directions on opposite sides of the plate, and hence all tendency of the plate to crowd to one side or the 35 other is avoided.

I may provide a receptacle for supplying fresh bran or other material to the plate between the two belts, if desired or found necessary, as shown in dotted lines at F in Fig. 3, 40 and in case plates of less length than the distance between the feeding-in and feeding-out rollers are being cleaned I may provide a pair of auxiliary feeding-rollers between the belts E and E', as shown at G G in Fig. 3.

45 In order to prevent the belts E and E' from becoming gummed up with oil or grease and an accumulation of bran or other material employed, I provide one or more cleaning-brushes H, suitably secured to the frame and 50 adapted to engage the cleaning side of the belt. I also provide a trough or receptacle I, having an inclined bottom located beneath the machine to catch the bran after it has been used, and it may then be used over 55 again, if desired. In Fig. 2 I have shown in dotted lines at J an elevating-conveyer for carrying the said material up and delivering it into the box D, so that it may be used again.

60 In Fig. 1 I have shown a vertical box K, engaging the rollers of one pair of belts, and by supplying the box with bran or other material it will be fed to the belts as they are carried through the box by the rollers. I 65 may employ one of said boxes, as shown in Fig. 1, or one for each pair of rollers, or I

may provide other means of supplying bran to the belts.

In Fig. 6 I have shown a box or hopper L at each end of the pair of belts, having discharge apertures or spouts l l, adapted to discharge the absorbent material upon the belts to facilitate their operation.

In order to insure the belts engaging the sheet of metal with sufficient friction to clean 75 and polish it effectively, I may prefer to provide the bearings for certain of the rollers which carry the belts with adjusting devices for adjusting the tension of the belts and also for adjusting the upper belt toward the 80 lower, or vice versa. In Figs. 1 and 2 I have shown one arrangement for accomplishing this. In the construction shown in said figures the bearings for one roller of each of the lower belts is adjustable to tighten the 85 belt, as shown at e⁴, Fig. 2, and the bearings of the rollers for the upper belts are provided with means for adjusting them toward and from each other and also vertically toward and from the other belt. In this instance I 90 have shown the bearing-supports for the upper-belt rollers provided with recesses e⁵, (see Fig. 2,) in which are located two triangular blocks e⁶, in the upper one of which is located the bearing for the roller. Set-screws 95 pass through the bearing-support and engage the blocks e⁶ e⁶, which have their inclined faces in engagement, so that by means of said blocks and screws the rollers may be adjusted farther apart to tighten the belt and 100 also vertically to bring it nearer the other belt. Any other adjusting means may be employed for accomplishing this result, and I may provide the bearings of one roller of each belt with a tension spring or weight to 105 exert a constant tension upon the belt, if desired, as indicated in dotted lines in Fig. 2.

The adjusting devices before described will also be used to adjust the belts nearer together to compensate for the wear of their 110 surfaces by friction in passing over the sheet metal in cleaning and polishing the same.

If it is desired to further secure the frictional engagement of the belts with the plates to be cleaned, I provide a series of compression-rollers M M, as shown in Fig. 6, or other compressing devices to hold the belts E' together in close frictional contact with the plates as they pass through the machine. One set of such rollers will have their bearings provided with set-screws or other adjusting means for regulating the amount of pressure brought to bear upon the belts.

In Fig. 7 I have shown a construction in which only a single belt is employed to rub both sides of the plate, instead of two, as in the other figures. In this figure the belt E² passes over suitable rollers E³ E³ and has its inner surface provided with sheepskin or other material to engage the sheet metal to be 120 cleaned. One side of the belt is engaged by a pair of idle-rollers E⁴ E⁴ and held adjacent 125

to the other portion to operate with it upon the sheet metal. In this figure I have shown a compressing device consisting of a stationary guide-plate N, engaging the outside of the belt on one side of the path of the metal sheet, and an adjustable plate N', engaging the belt on the other side, the adjustment of the plate N' being secured by set-screws, as shown, or other means.

10 In Fig. 5 I have shown a slightly-modified form of machine, in which I employ but a single pair of polishing and cleaning belts and locate the box D' for holding the bran or other material between the feeding-in rollers and the said belts. The box is shown adapted for reciprocation, as before described with reference to Fig. 1. The construction and operation of the parts shown in this figure are the same as before described, the only difference 15 being in the location and arrangements of the parts.

10 In Fig. 8 I have shown my improved machine adapted and arranged to clean the iron plate before it passes to the tinning-bath. 20 In this form the feeding-in and feeding-out rollers will be employed, as before described; but the belts E², instead of being supplied with sheepskin, will be provided with suitable brushes O, as shown, which will engage 25 the metal plates. The hoppers L' L' will be filled with sand or other abrasive material, which they will feed to the brushes to assist 30 in cleaning the metal plates, and a water-pipe P will be located and supported in position 35 to supply water to the plates as they pass through the machine, so that they will be thoroughly scoured.

By making these slight variations it will be seen that the machine can be adapted for use 40 in cleaning the sheet-iron before it passes to the tinning-bath.

While I have described and shown my improved machine adapted to operate on sheet metal passing through said machine in a horizontal position, it is obvious that the machine 45 could be arranged to operate on the metal in a vertical position, if desired.

In Fig. 5 I have shown the box D' for holding bran or other absorbent material provided 50 with apertures in the bottom of the same. This enables the bran to sift down and constantly bring fresh portions into contact with the surface of the metal sheets as they are passed through said box, and said box may 55 be located in rear of the feeding-in rollers, as shown in this figure, or in front of them, as shown in Figs. 1, 2, and 3.

It is also obvious that instead of giving the 60 cleaning-belts a continuous travel I may have them reciprocated across the path of the metal, if found desirable, as shown in Figs. 9 and 10. In these figures I have shown the shaft P of one of the feeding-rollers provided with an eccentric Q and an eccentric-rod q, 65 which is connected pivotally with a pivoted gear-segment R. The segment R is in en-

gagement with a pinion s on a shaft S, which is also provided with a bevel-wheel s', engaging a pair of bevel-wheels t on a shaft T, upon which the supporting-rollers for one end 70 of two of the cleaning-belts U U are mounted, each of said rollers driving the roller of the belt below by means of sprocket-chains u, as in the other figures. By this means the cleaning-belts will be driven first in one direction 75 and then in the other, instead of having a continuous movement.

I do not desire to be limited to the exact details of construction herein shown and described, as variations may be made therein 80 without departing from the spirit of my invention.

What I claim, and desire to secure by Letters Patent, is—

1. In a machine for cleaning sheet metal, 85 the combination with the feeding devices, of cleaning belts having their metal engaging sides provided with a coating of fibrous absorbent material and stationary brushes for engaging the said fibrous material, substantially as described.

2. In a machine for cleaning sheet metal the combination with the feeding devices, of a pair of cleaning belts having their metal engaging sides provided with a coating of 95 fibrous material, means for supplying absorbent material to the portions of the belt adapted to engage the metal, and brushes engaging portions of the belt out of the path of the metal, for cleaning them and removing the 100 used absorbent material, substantially as described.

3. In a machine for cleaning sheet metal, the combination with the feeding devices, of the reciprocating receptacle for cleaning material, disposed transversely of the travel of 105 the metal through the machine and the cleaning belts, substantially as described.

4. In a machine for cleaning sheet metal, the combination with the feeding devices, of 110 a pair of cleaning belts, a receptacle for cleaning material partially surrounding portions of each of said belts, whereby said belts will receive cleaning material while passing through said receptacle, substantially as described.

5. In a machine for cleaning sheet metal the combination with the feeding devices, of a pair of cleaning belts disposed horizontally 115 one above the other, and a vertically disposed receptacle for cleaning material partially enclosing portions of each of said belts located at one side of the machine, whereby said belts will receive cleaning material while passing through said receptacle, substantially 120 as described.

In testimony whereof I affix my signature in presence of two witnesses.

CHARLES ALBERT WETTENGEL.

Witnesses:

L. P. WHITAKER,
